Garrison Smith & Henry Brown, of Philadelphia, Pa.

Assignors to
Abbott and Noble, of same place,
Letters Patent No 1284, Dated July 3, 1860.

The schedule referred to in these Letters Patent, and making part of the same.

To all whom it may concern:

Be it Known that we, Garrison Smith and Henry Brown, both of the city of Philadelphia, State of Pennsylvania, have invented or produced a new and original design for the plates of a cooking stove, termed the "Telegraph", and we do hereby declare:... the accompanying drawing and following explanation of the same, to be a full, clear and exact illustration and description of the said design.

Fig. 1. of the drawing, representing the front plate of the stove.

Fig. 2, one of the doors for the same.

Fig. 3. the oven door of one of the side plates, and

Fig. 4. the small door of one of the side plates.

The front plate Fig. 1. has a door A, edged with a certain moulding which incloses a foliated ornament, and the doors Figs. 2, 3 and 4. are also edged with plain mouldings inclosing scroll and foliated ornaments, those of one door being similar in character to those of the other doors.

We claim the ornamental figures and forms represented in and by the accompanying drawing the whole forming plates for an ornamental Cooking Stove.

Des. 1284

In testimony whereof, we have signed our names to this Specification in the presence of ten subscribing witnesses.
